CLAIM

The ornamental design for a dispenser, as shown and described.

DESCRIPTION

FIG. 1 is a front elevational view showing my new design for a dispenser;

FIG. 2 is a rear elevational view thereof;

FIG. 3 is a left side elevational view thereof;

FIG. 4 is a right side elevational view of thereof; and,

FIG. 5 is a top plan view thereof.

The claimed portion of the dispenser extends between the dash-dash-dash line on the top portion of the dispenser body to the bottommost contour line on the bottom portion of the dispenser and includes the bottommost contour line on the bottom portion of the dispenser. The dash-dash-dash lines are included for the purpose of illustrating portions of the dispenser that form no part of the claimed design.
